FRANK HUMPHRIS, OF PARKSTONE, ENGLAND.

PRESS TOOL FOR PUNCHING AND STAMPING SHEET METAL AND THE LIKE.

Application filed November 18, 1926, Serial No. 149,172, and in Great Britain November 26, 1925.

This invention consists of improvements in and relating to press-tools for punching and stamping sheet-metal and the like and comprises one or more blanking-dies and one 5 or more punches and so-called die-punches and so-called punch-dies together with their die-carrying and punch-carrying-plates or holders, this invention includes their mode of arrangement and their parts, their opera- 10 tion and also the construction of the said press-tools, but whatever mode of arrangement is employed in press-tools made accord- 15 ing to this invention, there is preferably used for producing each article thereby, one blanking-die, in which or with which there 20 is provided a punch, hereinafter called the die-punch, and to coact with the said blank- 25 ing-die and die-punch there is provided on a punch-carrying-plate or holder, one punch 30 in which there is also provided a die, here- 35 inafter called the punch-die.

According to this invention there is embodied in each article-producing press-tool-combination, irrespective of whether such is 40 employed singly in a press or like machine, or whether two or more press-tool-combinations are employed and arranged in sets, or in gangs, what may be described as a combined punch-and-die which serves to coact 45 with a combined die-and-punch at one and the same time, in such a manner that the blanking or punching from a sheet of metal or material and also the stamping, raising, folding, curling or bending as well as the 50 ejecting of one or several finished-articles, as the case may be, from the so-called press-tools or tool, is accomplished at each recipro- 55 cative or operative-stroke of a press or other machine in which one or more of the said 60 press-tool-combinations are mounted, in addi- 65 tion the said press-tool-combinations are ar- 70 ranged so that they will eject one or several finished-articles, as the case may be, without passing the said article or articles back 75 through the hole or holes or perforation or 80 perforations in the sheet or stock from which 85 it has or they have been cut, and therefore 90 stock can be fed between what is hereinafter 95 described as the above-stock and the below- 100 stock members of the said press-tools when 105 these have only a very small daylight or gap between them. According to this inven- 110 tion all finished-articles are ejected mechani- 55 cally into channel-ways or conduits provided in some of the parts or members of the be-

low-stock press-tools for conveying the finished-articles out of the press or other machine in which the said press-tool-com- 60 bination or combinations is or are mounted.

To ensure the finished-articles being 65 mechanically ejected there is provided accord- 70 ing to this invention above-stock and also below-stock ejectors, as hereinafter more fully described; these ejectors not only eject 75 every finished-article from the press-tools, 80 but they also prevent clogging or choking of 85 the die-members of the said press-tools which clogging or choking might occur if 90 every finished-article was not mechanically 95 removed therefrom by the said ejectors be- 100 fore a succeeding operation takes place on the stock by the said die and punch-members.

To give a more clear understanding of this invention it is necessary to define the relative positions of the die-and-punch members 75 employed which coact one with the other, also how the so-called stripper-plate or its equivalent and the die-carrying-plate or its equivalent and the punch-carrying-plate or holders or the like equivalents therefor 80 are incorporated in, or are arranged to operate in conjunction with the punching, blanking, raising, forming and bending- 85 members of the said press-tools and so as to make this more easily understood it should be observed that all or any members of the 90 said press-tools, made according to this in- 95 vention, which are located above that face of a sheet, plate or other stock, in a press or other machine, or on the ram-side thereof, 100 will for such location purposes, be hereinafter referred to as above stock-members, and any or all of the members of the said press-tools, made according to this invention, which are located below that face of a sheet, 105 plate or other stock, or on the bolster-side thereof, will for such location purposes, be hereinafter referred to as below-stock-members, and the description above-stock-members and below-stock-members will be used 110 hereinafter.

When producing articles by the press-tools made according to this invention, it will be necessary in many cases to vary the form of, or placement of some of the com- 105 ponent-parts thereof so as to enable the man- 110 ufacture of different kinds and shapes of articles to take place; but for simplicity the invention will now be described and illus- 115 trated as it is applied in the production of 110

longitudinally-folded, creased or curled-nails, and a cupped or drawn article, which are cut out from sheet-metal and finished in one operation, preferably in rows and nearly 5 across one way of the sheet, or so as to cut and finish a row of nails or articles at each operative-stroke of the press or other machine in which the said press-tools are mounted; but it is to be understood that this 10 description and the illustrations are given merely by way of example and that many other kinds of articles can be produced either one at a time or several at one and the same time by the press-tools made according to this invention.

In the accompanying drawings:—

Figure 1 is a view partly in section illustrating how one form of above-stock-punch, in which there is a punch-die, coacts with 20 a below-stock blanking-die and cuts out a blank from sheet stock and how this blank just after it has been cut out is held firmly against the face of the above-stock-punch by below-stock ejectors which are mounted 25 in a resilient manner and so as to slide in the below-stock die-punch or drawing-post.

The operations to produce a finished article are as follows:—The blank after it has been cut from the stock is held firmly against 30 the cutting or blanking-face of the above-stock-punch until the said blank makes contact with the below-stock die-punch and between the forming faces of which and those provided in the above-stock punch-die the 35 said blank is bent, crinkled, raised and/or embossed so as to produce a finished article, but it should be observed that whilst the blanking of the stock, the bending of the blank and the finishing and also the ejecting 40 of a finished article from the forming faces of the press-tools take place, the stock from which the said blank has been cut, to prevent distortion thereof, is pressed on to the below-stock blanking-die by an above-stock 45 spring-actuated stripper, which not only strips the stock from the above-stock-punch but also serves as a pressure-plate, and the below-stock blanking-die or the pressure-plate, or both, are optionally provided with 50 points, sharp ridges, or protuberating parts which are arranged to be close to the cutting-edges of the said blanking-die or to be close to the hole in the pressure-plate through 55 which the above-stock blanking-punch slides as the case may be, and in this blanking-punch above-stock ejectors are provided to eject finished articles out from the punch-die therein.

Figure 2 is a view illustrating one position 60 that the above-stock-punch with the ejectors therein and the blank, all of which are shown in Figure 1, take as they move towards the below-stock die-punch, this view also shows how the below-stock ejectors slide or are moved into the below-stock die-punch or

drawing-post before the forming of the blank into an article takes place. This view clearly shows the blank in contact with the below-stock-ejectors.

Figure 3 is a view illustrating the position 70 that the above-stock-punch and the ejectors therein and the below-stock-ejectors shown in Figures 1 and 2, are constrained to take after the blank has been forced around and into the below-stock die-punch, and thus 75 formed, or bent, or crinkled and/or embossed into a finished article.

Figure 4 is a view illustrating the position 80 that the above-stock-punch and the ejectors therein and the above-stock stripper-and-pressure-plate and the below-stock-ejectors shown in Figures 1, 2 and 3, after an article has been produced, return to, to enable the stock to be fed forward into the position as shown in this view ready for a repetition 85 operation to occur, this view also shows how the below-stock-ejectors eject a finished-article from out of and off the below-stock die-punch or drawing-post into a chute through which the said article falls, this 90 view also shows the position that the above-stock-ejectors take in the punch-die, after they have ejected the finished-article out of the said punch-die. In this view the cross-sectional form of a folded-nail is shown and 95 illustrates how a folded-nail is ejected by the below-stock-ejectors into the channel-way or chute.

Figure 5 is a view partly in section illustrating how another form of above-stock-punch, in which there is a punch-die, coacts with a below-stock blanking-die and cuts out 100 a blank from sheet-stock, by first cutting one edge of the said blank and then cutting the ends thereof shearwise and finally severing the said blank from the stock by cutting the other edge thereof. This view also illustrates how this blank is held firmly against the face of the above stock-punch by the below-stock ejectors, which are mounted in a resilient manner so as to slide in the below-stock die-punch or drawing-post. Operations of a like kind to those described with 105 reference to Figure 1 of the drawings for producing a finished article are employed.

Figure 6 is a view illustrating the position of the above-stock-punch and the ejectors therein as the above-stock punch and punch-die commences to bend the blank partly on and into the below-stock die-punch. 110

Figure 7 is a view illustrating the position 115 that the above-stock-punch and the ejectors therein and the below-stock-ejectors shown in Figures 5 and 6, are constrained to take after the blank has been forced around and into the below-stock die-punch and thus formed, or bent, or crinkled and/or embossed into a finished article.

Figure 8 is a view illustrating the position 120 that the above-stock-punch and the ejectors 125

therein, the above-stock stripper-and-pressure-plate and the below-stock-ejectors shown in Figures 5, 6 and 7, after an article has been produced, return to, to enable the stock 5 to be fed forward in a like manner and for the other purposes as described with reference to Figure 4 of the drawings. In this view the cross-sectional-form of a folded-nail is shown and illustrates how a folded-nail is ejected by the below-stock-ejectors 10 into the channel-way or chute.

Figure 9 is a view partly in section illustrating how still another form of above-stock-punch, in which there is a punch-die, 15 coacts with a below-stock blanking die just before it cuts out a blank from sheet-stock and how this blank after it is cut out will be held firmly against the face of the above-stock-punch by the below-stock ejectors in a like manner and for the other purposes as 20 described with reference to Figure 1 of the drawings.

Figure 10 is a view illustrating the position that the above-stock-punch with the 25 ejectors therein and the blank all of which are shown in Figure 9 take when the blank is in contact with the below-stock die-punch and the below-stock ejectors and before it is bent or formed into a finished article.

30 Figure 11 is a view illustrating the position that the above-stock-punch and the ejectors therein and the below-stock-ejectors shown in Figures 9 and 10 are constrained to take after the blank has been forced 35 around the below-stock die-punch and thus formed, or bent, or crinkled and/or embossed into a finished article.

Figure 12 is a view illustrating the position that the above-stock-punch and the 40 ejectors therein, the above-stock stripper-and-pressure-plate and the below-stock-ejectors, shown in Figures 9, 10 and 11, after an article has been produced, return to, to enable the stock to be fed forward in a like manner 45 and for the other purposes as described with reference to Figure 4 of the drawings. In this view the cross-sectional form of a folded-nail is shown and illustrates how a folded-nail is ejected by the below-stock ejectors 50 into the channel-way or chute.

Figure 13 is a cross-sectional-view showing 55 two of a set of article-producing press-tool-combinations, which with others of the same kind are mounted side by side in a press or other machine and arranged in a two-row form of placement, or as two gangs, or sets, and in which the coacting dies-and-punches and the parts which are only partly illustrated in Figures 1 to 4 are employed and 60 these when they are arranged as shown in this view, are capable of producing two rows of finished-articles from a sheet of metal or material at each operative-stroke of a press or other machine in which they are mounted. 65 In this form of carrying the invention into

effect different shapes or patterns of blanking-dies may be used and may be made sectional or otherwise and secured in any known manner to the below-stock punch-holder-plate. 70

Figure 14 is a side-elevational-view partly in section of some of the article-producing press-tool-combinations of the kind shown in Figure 13, and illustrates the form of placement of the above-stock-punches and of the 75 below-stock die-punches and of the channel-ways or chutes.

Figure 15 is an enlarged view partly in section of one below-stock punch-holder-plate and one blanking-die, of the kind 80 shown in Figures 13 and 14, and illustrates clearly how the below-stock-ejectors are slidably and resiliently-mounted so that they will slide and also operate in the below-stock die-punch and eject a finished-article into 85 the channel-way or chute.

Figure 16 is a plan-view partly in section of some of the parts shown in Figures 13 and 14, and illustrates how the below-stock blanking-dies are arranged in their form of 90 placement and are secured to the below-stock punch-holder-plate and how the above-stock-punches are arranged and also guided in the above-stock stripper-and-pressure-plate.

Figure 17 is a plan view of the below-stock 95 blanking-dies, of the kind shown in cross-section in Figures 1 to 12. It will be obvious that the contour of the cutting-edges of these dies may be given different shapes to suit the form of blank they are designed to cut, 100 which is simple as they are sectional-dies.

Figure 18 is an enlarged view in perspective showing one of the half-die-blocks of a modified form of below-stock blanking-die 105 of the kind employed in the press-tool-combination shown in Figure 20 and illustrates how the below-stock-ejectors project through and slide in slots in the below-stock die-punch. This view shows how protuberating-points are provided near the cutting-edges 110 of the below-stock blanking-die so as to indent the stock, local to the edge thereof which is being cut, these prevent the stock from stretching or distorting whilst the cutting of a blank takes place. 115

Figure 19 is a part-sectional-view illustrating how the below-stock-ejectors, of the kind used in the three-piece below-stock-punch of the press-tool-combination shown in Figure 21, slide and are guided in slots 120 provided in the centre-plate located between two outer-plates or shear-blades and the three-pieces of this below-stock-punch are secured together by screwed-members, rivets or the like of any known kind. 125

Figure 20 is a cross-sectional-view showing a modified form of one, or of one of a set, or gang of article-producing-press-tool-combinations in which the below-stock blanking-die is mounted on and to the be- 130

low-stock spring-actuated die-carrying-plate which retrocedes when depressed by the strong spring-effort of the above-stock spring-actuated pressure-plate in such a manner that the above-stock-punch cuts out a blank from the stock and folds it into a finished article around the below-stock-punch from which it is ejected by the ejectors into the channel-way or chute.

10 Figure 21 is a cross-sectional-view showing another modified form of one, or of one of a set, or gang of article-producing press-tool-combinations in which a below-stock spring-operated stripper-plate is caused to 15 retrocede by the above-stock blanking-die before blanking takes place. In operation the below-stock-punch, firstly cuts a blank into the above-stock blanking-die, and lastly bends or forms it between the faces of the 20 above-stock die-punch and the faces of the below-stock punch-die in such a manner that a finished-article results, after which the moving-parts of this modified-form of article-producing press-tool-combination return 25 to the positions illustrated in this view; but during this return movement, the below-stock ejectors which are mounted and also secured in and also move with the below-stock stripper-plate, eject any finished-article 30 that has been produced by and between the die and punch members out of the die-cavity in the below-stock-punch, and the above-stock-ejectors also eject it from out of the above-stock blanking-die-cavity and 35 away from the above-stock die-punch into the channel-way or chute.

Figure 22 is an enlarged view in perspective of a part of an above-stock punch, and clearly shows the punch-die therein, this 40 above-stock-punch is shown in cross-section in Figures 9 to 12 and in Figure 20, this view illustrates clearly the cutting-face of the said punch, the punch-die-cavity and also the perforations in which the above-45 stock-ejectors, used in this form of punch-die, slide plunger-wise.

Figure 23 is an enlarged view in perspective of a part of a below-stock die-punch, of the kind shown in cross-section in Figures 50 9 to 12 and in Figure 20, and illustrates the slots therein in which the below-stock-ejectors slide and by which they are guided.

Figure 24 is an enlarged view in perspective of a part of a three-piece below-stock-punch and punch-die, of the kind shown in cross-section in Figures 19 and 21; this view 55 illustrates the form of placement of the component-parts thereof and how one blade which serves to shear or cut one of the edges 60 of the blank is provided with slots which are located below the cutting-edge of this blade, this view also illustrates how the centre-plate of this three-piece below-stock-punch is provided with slots which are arranged 65 to communicate with, or open into the die-

cavities in the punch-die thereof, and it is in these slots that the ejectors slide to make contact with any finished-article as they eject it. The three-pieces of the said punch and punch-die are secured together by means of 70 rivets, screws or the like of the known kind.

Figure 25 is an enlarged view in perspective of a part of an above-stock die-punch, of the kind shown in Figure 21, this view 75 illustrates the perforations in which the above-stock-ejectors, which are used in this form of die-punch, slide plunger-wise.

Figure 26 is a view partly in section illustrating how a more complex form of above-stock-punch in which there is provided forming and embossing dies, is constructed so as to have two cutting-faces one for blanking from the stock and one for piercing the blank, and a drawing member for drawing and cupping the part piercing out from the 85 larger blank, the said above stock punch 90 contacts with a below-stock blanking-die to cut out a blank and also with below-stock spring-actuated ejectors for carrying the blank on to a below-stock die-punch or 95 drawing-post in which there is provided two drawing dies and a piercing-punch and faces for forming and embossing the blank into a finished-article in a single-action, after 100 which the said article is ejected by the ejectors into a channel-way or chute at the side of the below-stock die-punch. Operations of a like kind to those described with reference to Figure 1 for producing a finished article are employed.

Figure 27 is a view partly in section illustrating the position that the punch, die-members and ejectors shown in Figure 26 take when an article is finally formed. This view shows a small cup produced at the same time and how the said cup is ejected through a hole in the below-stock die-punch or drawing-post.

Figure 28 is a view partly in section illustrating the punch and die members and ejectors in the position to which they return before commencing to blank the stock. In this view the cross-sectional form of a finished article is shown as it is being ejected by the ejectors into the channel-way or chute.

Figure 29 is a part sectional plan view taken on the line A, B Figure 27 and shows clearly the position of the channel-way or chute at the side of the below-stock die-punch or drawing-post and the arrangement of the ejectors.

Figure 30 is a side elevational-view of a forked below-stock ejector of the kind employed in the below-stock die-punch or drawing-post shown in Figure 26.

Figure 31 is an elevational view showing an enlargement of the finished-article which has been produced by the punches and dies as shown in Figure 26.

Figure 32 is a perspective view showing a 130

nail which has been produced between the forming-faces and by the punches and dies shown in Figures 1 to 4.

Like letters of reference refer to like parts throughout the drawings.

The essential parts of the press-tools forming the subject of this invention are made up of pieces which are attached by bolts, screws or the like either directly or indirectly, to the ram m or the bolster s (Figures 13, 14, 20 and 21) of a press or other machine. In the simplest form of carrying this invention into effect Figures 1 to 12 of the drawings illustrate parts of some of the members of the press-tools used in this invention to give a clear understanding as to how the operations of producing an article are accomplished, and show an above-stock-punch a in the face of which is formed an above-stock-die a^1 ; in the above-stock-punch a there is preferably a minimum of two above-stock-ejectors n which slide in holes or perforations a^2 , Figures 22 and 25. In Figure 1 of the drawings the above-stock-punch a is shown in its position after having just cut a blank w from a piece of stock v by coacting with the blanking-die c , this view shows the below-stock-ejectors t which are located so as to operate at, or in one side of the below-stock blanking-die c , which below-stock-ejectors t are slidably-mounted in the below-stock-punch-plate d and actuated by a spring t^1 in such a manner as to hold the said blank w against the blanking-face of the above-stock-punch a until it has been carried on to the below-stock die-punch g . The above-stock-punch a is connected through the medium of a holder or holder-plate a^3 and screws or the like a^4 (Figures 13 and 14) to an above-stock plate r which is preferably mounted to the ram m of the press or other machine. As the above-stock-punch a is moved towards the base-plate k of the press-tools or towards the bolster s of a press or other machine it slides in and is guided by a hole b^2 in the above-stock stripper-and-pressure-plate b which is actuated by springs b^1 so that the said pressure-plate b can deliver pressure on the stock v . The below-stock-ejectors t which hold the blank w , slide in the below-stock die-punch g and in a hole d^2 (Figure 15) provided in the below-stock die-carrying and punch-holder-plate d in which there is provided a spring t^1 for actuating the ejectors t and an adjusting-screw d^3 for giving the desired compression to the said spring t^1 . When a blank w has been forced around and into the die-cavities g^1 of the below-stock die-punch g by the above-stock-punch a as shown in Figure 3 of the drawings it is formed into an article x and this view illustrates how the blank w , which has been carried by and between the spring-actuated below-stock-ejectors t and the above-stock-

punch a on to the below-stock die-punch g , is given a sinuous outline in cross-section and how the said blank w is changed into an article x , after which operation the above-stock-punch a recedes from the below-stock die-punch g , and the below-stock-ejectors t constrained by their actuating-springs t^1 follow the above-stock-punch a and eject the finished article x , as is shown clearly in cross-section in Figure 4 of the drawings, into the channel-way or chute u without passing the said article x back through the stock v , and the said stripper-plate b strips the stock v off the above-stock-punch a .

It will be obvious that various articles can be produced by altering the shape of the forming and cutting-faces of the members of the press-tools the subject of this invention, this is illustrated by way of example in Figures 1 to 12 of the drawings. In Figure 5 of the drawings a modification is illustrated in which a blank w is cut firstly along one edge thereof and then along the ends thereof and finally the blank w is cut or severed from the stock v along the other edge thereof; this method of cutting the blank w is advantageous particularly when forming an article as shown in cross-section in Figures 7 and 8 of the drawings; but the means for bending and forming are similar to those shown in Figure 3 and 4 of the drawings, as is also the operation of the press-tools. Figure 9 of the drawings illustrates an above-stock-punch a in the face of which there is formed a single-die cavity a^1 which coacts with a below-stock die-punch g ; this view shows the above-stock-punch a before it has cut out a blank w ; but it should be observed that the below-stock-ejectors t are so arranged that they do not make contact with the stock v at any time, but only with the blank w to hold it against the blanking-face of the above-stock-punch a immediately the said blank w is cut. The operations or stages of progress in making an article as shown in Figures 9 to 12 of the drawings are similar to those illustrated in Figures 1 to 4 of the drawings in which views the different positions taken by the above-stock-ejectors n can be seen clearly during the operations on the stock v and on the blanks w , and also how the above-stock-ejectors n operate to eject finished articles x out of the die-cavities a^1 in the above-stock-punch a immediately it begins to move away from the below-stock die-punch g . In the most simple form of carrying this invention into effect and where a large output of similar articles at a rapid rate is desired, particularly when the said articles are made from thin sheets of metal or material, the press-tools the subject of this invention are then embodied and assembled in a manner like or similar to the example

shown in Figure 13 of the drawings, which illustrates how the component-parts of the press-tools which are only partly shown in Figures 1 to 12 of the drawings are preferably assembled to give them rigidity, on so-called top and bottom punch and die-bases, or on an above-stock-plate *r* and a below-stock base-plate *k*, which in either case are provided directly or indirectly through other members with guides or guide-pins *d*⁵ or the like and the whole assembly is preferably arranged so as to have one or more sets or gangs of press-tools located in a form of placement either as one row, or as two or more rows side-by-side so that they will cut out and produce from sheets of metal or material several articles *x* or the like in one or more rows at each operative-stroke of a press or other machine in which the said press-tools are mounted.

It has been found advantageous to assemble the press-tools, the subject of this invention, so as to have a form of placement which permits them to be arranged in a frame or on holders or plates sub-press-wise so that the whole assembly thereof can be removed from or placed into a press or other machine or between the ram and bolster thereof or the equivalents therefor without having to dismantle the component-pieces comprised in the press-tools, the subject of this invention; but it is to be understood that such is not an essential but only an advantage as the above-stock-members may be secured to the ram of a press or other machine and the below-stock-members may be secured to the bolster of a press or other machine, and the guiding to ensure that the members of the press-tools will coact correctly may be done either by guide-pins such as *d*⁵ (Figure 13) or pins or bolts such as *e*² or *f*³ (Figures 20, 21) which are either held or slide in bosses or lugs such as *d*⁴, *b*⁴, *e*¹, or *f*², as the case may be or they may be guided by the guides provided for the ram of the press or other machine in which they are mounted.

The below-stock-ejectors *t* are, in the examples illustrated in Figures 1 to 15 of the drawings, actuated by relatively weak springs *t*¹ to those which actuate indirectly the below-stock-ejectors *t* illustrated in Figures 18 to 21 of the drawings, and these relatively weak springs *t*¹ are located in guide-holes *d*² which also serve as guides for the below-stock-ejectors *t* to slide in. To vary the effort exercised by the springs *t*¹, adjusting-screws or the like *d*³ are employed, these are screw-threaded as are also the guide-holes *d*².

In a modified form of carrying this invention into effect as partly shown in Figure 18 of the drawings and also by way of example in Figure 20 of the drawings, it will be observed that the above-stock-members of

the press-tools are of a like character to those illustrated in Figures 1 to 14 of the drawings; it will also be observed that the arrangement of some of the parts hereinbefore described of the press-tools is different and also that extra parts have been added to the below-stock-members thereof as hereinafter described; the one-piece below-stock die-carrying and punch-holder-plate *d* of the kind employed when carrying the simple-form of this invention into effect is in this modified-form divided or in two separate parts or what may be described as parts formed by cutting the simple form of punch-holder-plate *d* into two pieces, one piece thereof is given the reference letter *d*¹ (Figures 19, 20, 21) in the drawings and this piece holds through the medium of screw-threaded members *g*² the below-stock die-punch *g* and is secured by bolts or the like *d*³ to the base-plate *k*, but the other piece thereof is given the reference letter *e* in the drawings and on or in which the below-stock blanking-die *c* is mounted and secured as are also the below-stock-ejectors *t*, is in this modification slidably-mounted on guide-pins or bolts *e*² or the like equivalents which are arranged to pass through holes in lugs *e*¹ on the said other piece *e* and these said guide-pins or bolts *e*², the head-parts of which are arranged to serve as stops, are screw-threaded into the said one piece hereinafter referred to as the punch-holder-plate *d*¹ between which and the other piece hereinafter referred to as the below-stock retroceding die-carrying-plate *e* in which the below-stock blanking-die *c* and also the below-stock ejectors *t* are mounted and secured, there are provided powerful springs *e*³ or their equivalents, in the form of rubber-blocks or the like, which serve to separate the pieces *d*¹ and *e* and to actuate or give adequate force to the ejectors *t* so that they will eject any article however stiff or resisting it may be, from off the die-punch *g*.

The said below-stock-ejectors *t* illustrated in Figures 18 and 21 of the drawings are secured against any independent movement in any direction other than with the below-stock retroceding die-carrying-plate *e* or the below-stock stripper-plate *f* and in a hole or holes *f*¹ (Figure 19) provided therein, they are secured by screw-threaded members *t*², rivets or the like and as a result thereof the said below-stock-ejectors *t* obtain the advantage of the effort exercised by the powerful springs *e*³ or *f*⁴ or their equivalents, which actuate the retroceding die-carrying-plate *e* or the below-stock stripper-plate *f*, when they are ejecting articles off the below-stock-die-punch *g*, or the below-stock-punch *h* as the case may be, this spring-effort is essential, where articles are made from thick sheets of metal or material or are of large

dimensions, as understood by press operatives, have to be ejected by ejectors such as *t* which are actuated by or through the medium of a resilient-member or members.

5 A further and very important modification of the press-tools made according to this invention is illustrated in Figure 21 of the drawings in which modification the blanking-die *o*, its spring or mechanically 10 operated ejectors *n* of which there may be several in each above-stock-die-punch *a*⁵, are located above instead of below the stock in such a manner that the said blanking-die becomes an above-stock blanking-die *o* having 15 therein an above-stock die-punch *a*⁵ this with the said blanking-die *o* is mounted in, or on, and secured to an above-stock-holder or plate *p* by screws or any known means or so that in this assemblage and arrangement 20 of the component-parts of the press-tools the subject of this invention, no above-stock stripper-plate is employed or is necessary, for the reason that the punch which requires a stripper-plate and which coacts with the 25 said blanking-die *o* is in this modification located below the stock and is secured to the below-stock punch-holder-plate *d*¹ by bolts or screwed members *g*²; the construction in this modification of the invention facilitates 30 the removal of the blanking-die *o* for grinding and also the removal and replacement of the die-punch *a*⁵ and of the ejectors *n* and their springs *n*¹ as these are contained or housed in the said holder *p* and as a result 35 of this arrangement and form of placement of the punch *h* and of the blanking-die *o* it is possible to employ a below-stock stripper-plate *f* or its equivalent with its attendant advantages, as by doing this the 40 operations on the stock can be observed easily; but as it is necessary in all cases to strip the stock *v* after it has been blanked or remove it from off the said punch *h* a below-stock stripper-plate such as *f* is an 45 essential and is employed in this modification of carrying this invention into effect.

In this modification the punch-holder-plate *d*¹ and the stripper-plate *f* are separate pieces resembling two pieces *d*¹ and *e* employed in the modification shown in Figure 20 of the drawings, but in this further modification a below-stock blanking die and retroceding die-carrying-plate are not employed, but a below-stock stripper-plate *f* is employed which substitutes the above-stock stripper-plate *b* used in the other assemblages or arrangements illustrated.

50 In the modification illustrated in Figure 21 of the drawings the stripper-plate *f* is actuated by springs *f*⁴ or their equivalents which move the said stripper-plate *f* and the below-stock-ejectors *t* in a manner similar to that employed for moving the die-carrying-plate *e* shown in Figure 20 of the drawings and the below-stock-ejectors *t*

which are secured to or in the stripper-plate *f* serve to eject articles out from the below-stock punch-die *h*⁵; the stripper-plate *f* in this modification is guided and controlled in a manner similar to that employed for controlling the distance of travel or movement of the die-carrying-plate *e* shown in Figure 20 of the drawings, or the said stripper-plate *f* is guided by means of guide-pins or bolts *f*³ which are screw-threaded into lugs *f*² or the like provided on the stripper-plate *f* and the said pins or bolts *f*³ have heads thereon which are arranged to serve as stops or to regulate the distance of travel of the stripper-plate *f*, the said pins or bolts *f*³ are arranged to slide in holes in the lugs or bosses *d*⁴ provided on the below-stock punch-holder-plate *d*¹.

55 In a more complex form of carrying this invention into effect as partly shown in Figures 26 to 28 of the drawings, it will be observed that the above-stock-punch *a* has two cutting edges, one *a*⁶ for cutting the blank *w* from the stock *v* and the other *a*⁷ for piecing the blank *a*; it will also be observed that the punch *a* is provided with a forming and embossing die *a*¹ and a piercing-die *a*⁸ with a drawing-punch-member *a*⁹ therein; the punch *a* coacts with a below-stock die-punch or drawing-post *g* having 60 therein a drawing-die *g*⁸ and a below-stock piercing-punch *g*⁶ having therein a cupping-die *g*⁷ which communicates with a hole *g*⁷ through which the cup *a*¹ is ejected. The ejectors *n* and *t* in this modification are slidably-mounted in a manner similar to that shown in Figures 13 and 14 of the drawings. The finished article is ejected into the channel-way or chute *u* as hereinbefore described with reference to Figures 1 to 4 of the drawings.

65 In those forms of carrying this invention into effect where the below-stock die-carrying and/or punch-holder-plate *d* or *d*¹, as the case may be, is secured to a base-plate *k* by screwed-members *d*⁶ or the like, the base-plate *k* is in turn optionally secured by bolts *d*⁷ or the like to a bolster *s* or the like of a press or other machine.

70 In those forms of carrying this invention into effect an above-stock-stripper and pressure-plate *b* preferably with a hardened pressure-face-part *b*⁸ (Figures 13, 20) is employed and is actuated by springs *b*¹ or their equivalents, and is also optionally guided by either bolts *b*⁵ or guide-pins *d*⁵ or their equivalents, the punch or each punch *a* then slides in a hole or slot *b*² provided in the said stripper-plate *b* and each punch *a* is secured by any known means in or to a holder-plate *a*³ which is optionally secured by screws *a*⁴ or the like to an above-stock-base or plate *r* which in turn is optionally secured to a ram *m* of a press or other machine, and in each said punch *a*

or through holes a^2 therein the above-stock-ejectors n are slidably-mounted and are actuated by springs n^1 or their equivalents.

Where in the form of carrying this invention into effect an above-stock die-holder-plate p (Figure 21) is employed and serves also as a depressor for depressing a below-stock stripper-plate such as f , the said die-holder-plate p is secured by bolts q to an above-stock-base or plate r which in turn is optionally secured to a ram m of a press or other machine; in this form of carrying the invention into effect it will be observed that the said above-stock die-holder-plate p has above-stock-ejectors n therein which are slidably-mounted in holes a^2 provided in the above-stock die-punch a^5 , these above-stock-ejectors n are actuated by springs n^1 in a like manner to the above-stock-ejectors n slidably-mounted in the above-stock-punch a .

Any above-stock-ejectors n used in this invention may be of circular or other form in cross-section or they may be of plate-like-form.

The below-stock-ejectors t used in this invention may be of any form in cross-section, they are however preferably of plate-like-form or flattened at the parts thereof which make contact with the finished articles they have to eject; sloping or bevelled-edges are preferably provided thereon which facilitate the ejecting or removal of articles thereby from either form of below-stock-punch g or h , as the case may be. Where necessary shields g^4 as in Figure 15 are provided on the ejectors t or over the slots g^3 and h^3 to exclude any obstruction to the free movement of the ejectors t .

Channel-ways or chutes are provided in any assemblages of press-tools made according to this invention, through which all articles that are produced by the said press-tools pass or fall.

The blanking-dies such as c or o , or each one, or several of them in a set or gang, may be made so as to be in an integral piece of metal or they may be made as one or more sectional-dies from several separate pieces of metal, as shown in Figures 16 to 18 of the drawings, or from any suitable number of pieces or in any suitable number of parts and secured on ledges d^8 or the like Figures 4, 8 and 12, or to a die-holder-plate such as d or to e or to p , by screws c^2 or the like means.

The blanking-dies such as c or o and/or the stripper-plates such as b or f are optionally provided near the cutting-edges thereof or near to the hole therein in which a punch such as a or h enters or slides, with several small conoidal-points or jags such as c^1 , Figure 18, or alternatively and as substitutes therefor with one or more sharp protuberating-ridges optionally provided with saw-like teeth, any of these devices or means are

employed to indent the stock and to prevent that part thereof which is not cut out as a blank, from stretching or bulging whilst blanks are being cut therefrom.

The punches used in this invention such as a , a^5 or g may be made in one piece and provided with slots such as g^3 , Figure 23, or they may be made as two or more pieces such as h and h^1 , Figure 24, or as sectional-punches. In the case where the pieces h^1 and h are employed they are held or secured together by rivets or the like, or by screw-threaded-members such as h^4 . Slots h^2 are provided in the pieces h^1 and slots h^3 are provided in the centre-piece h to accommodate the ejectors t .

The press-tools the subject of this invention are arranged to produce a finished article from each blanking-die therein at each reciprocative-stroke of the punch which coacts therewith for cutting out blanks from sheet or other metal or material, or articles are produced by the said press-tools at each blanking-stroke thereof and are delivered away from the said press-tools at each return-stroke after blanking and forming has occurred.

The press-tools the subject of this invention have been devised to overcome known difficulties in the production of articles or blanks in rows at one time or at each blanking-stroke of the said press-tools, particularly when such rows extend nearly across the width, or the length, as the case may be, of a sheet of metal or other material, which sheet of metal or other material when operated upon by the known forms of punches and dies in a two or more follow-on process without conoidal-points or jags such as c^1 , or the sharp protuberating-ridges as are employed according to this invention, stretches, bulges or distorts at that part or those parts of the said sheet of metal or other material which is or are not cut out into blanks.

It is to be clearly understood that according to this invention, the blanking-dies, or the punches, or the punch-dies, or the die-punches, or either or all of them, as the case may be, will be given such forms or shapes for their shearing and/or folding, curling, raising, bending or forming-faces, as will allow them to coact in any manner when producing articles of different contours and/or shapes; and in addition any of the component-parts of the press-tools according to this invention is, or are provided with a channel-way or channel-ways or a conduit or conduits or a chute or chutes therethrough or therein, in which one wall or side thereof consists of one face of a blanking, folding or forming-punch, or like member, so that the said channel-way or channel-ways or the like serve to restrict blanks, or folded or finished-articles, or the like, in their path of

travel therethrough after they have been ejected from the forming-tools; and the provision of a channel-way, conduit, or of a chute which is located at the side of any 5 punch-member or the like in press-tools, is intended to be included in the spirit of this invention.

I claim:

1. A press tool comprising a forming 10 punch, a forming die, a blanking die through which the said forming punch is movable and an ejector having an oblique edge and movable by the forming punch and arranged to cooperate with the said forming punch to 15 support a blank cut from stock whilst it is moved through the blanking die to the forming die, said oblique edge providing means for ejecting a finished article laterally from the forming die.

2. A press tool comprising a blanking die, a stripper plate, a punch movable through said die and plate, a forming die coacting with said punch, a die plate supporting a forming die within a cavity therein and a 25 passageway arranged laterally to the forming die for conducting away from the forming die an article formed between the said die and punch, and an ejector having an oblique edge for ejecting the finished article 30 laterally into said passageway.

3. A press tool comprising a blanking die having a cutting edge for cutting a blank from sheet material presented thereto, protuberances on the face thereof near the cutting edge, a stripper plate, a combined blanking and forming punch movable through the stripper plate and blanking die, a forming die, and an ejector slideable on the said forming die and cooperating with the punch to 40 carry a blank sheared out by the punch from the blanking die to the forming die, said ejector being provided with an oblique ejecting edge.

4. A press tool comprising a movable 45 forming punch, a blanking die through which the movable forming punch passes to act as a blanking punch, a die plate having a cavity, a stationary forming die mounted in said cavity, said die plate having a passageway formed therein laterally to the said stationary forming die, and an ejector having an oblique ejecting edge and mounted to slide relatively to said forming die.

5. A press tool comprising a movable 55 forming punch, a blanking die through which the movable forming punch passes to act as a blanking punch, a die plate having a cavity, a stationary forming die mounted in said cavity, said die plate also having a 60 passageway formed therein laterally to the said stationary forming die, and spring supported ejectors slideably mounted in the said stationary forming die and each having an oblique ejecting edge.

6. A press tool comprising a movable

forming punch, a blanking die through which the movable forming punch passes to act as a blanking punch, means for retaining against the movable forming punch a blank 70 cut from stock by the said movable forming punch whilst it moves through the blanking die, a stationary forming die having an open passageway formed therein laterally to the said stationary forming die, and means integral with said blank retaining means for 75 ejecting a finished article laterally into said passageway.

7. A press tool comprising a movable forming punch, a blanking die through which the movable forming punch passes to 80 act as a blanking punch, a stationary forming die, means whereby a blank cut from stock by the blanking punch is transferred to the said stationary forming die, and means integral with a member of the said 85 blank transferring means for ejecting a finished article laterally from the forming die.

8. A press tool comprising a movable forming punch, a blanking die through which the movable forming punch passes to 90 act as a blanking punch, a resilient support for the said die, means for guiding the blanking die to move in alignment with the movable forming punch, a stationary forming die, and an ejector having an oblique 95 edge for ejecting the finished article from the forming die.

9. A press tool comprising a movable forming punch, a blanking die through which the movable forming punch passes to 100 act as a blanking punch, a resilient support for the said die, a ram carrying said forming punch, a stripper plate resiliently mounted on said ram, a stationary forming die, and a spring supported ejector slidably mounted 105 in the said stationary forming die and provided with oblique ejecting edges.

10. A press tool comprising a movable forming punch, a blanking die through which the movable forming punch passes to 110 act as a blanking punch, a stationary forming die, and a spring supported ejector slideably mounted in the said stationary forming die, said ejector having an edge cooperating with the movable forming punch to clamp 115 between them a blank cut out from stock by the said punch whilst the said blank is carried to the stationary forming die, and also having an oblique edge for ejecting a finished article laterally from the said stationary die.

11. A press tool comprising a movable forming punch, a blanking die through which the movable forming punch passes to act as a blanking punch, a die plate, a stationary forming die mounted in a cavity within the die plate and having a groove, a spring supported ejector slidably mounted in said groove in the said stationary forming die, said die plate having a passageway 125 130

formed therein laterally to the said stationary forming die, and a shield covering the side of the said groove opening towards the said passageway.

5 12. A press tool comprising a blanking die, a blanking and forming punch movable through the blanking die to cut out a blank from stock and push the same through the blanking die, a die plate, said die plate hav-

ing a passageway on the opposite side thereof to that on which the stock rests and a die cavity, a stationary forming die within said cavity, and a spring supported ejector provided with oblique edges for ejecting a finished article from the stationary forming die into the said passage. 10 15

FRANK HUMPHRIS.
